UNITED STATES PATENT OFFICE.

NIELS ANTON HANSEN, OF SEATTLE, WASHINGTON.

KNOCKDOWN CABINET.

1,113,432.

Specification of Letters Patent.

Patented Oct. 13, 1914.

Application filed May 21, 1912. Serial No. 698,797.

To all whom it may concern:

Be it known that I, NIELS ANTON HANSEN, a subject of the King of Denmark, and having declared my intention of becoming a citizen of the United States, residing at Seattle, in the county of King and State of Washington, have invented certain new and useful Improvements in Knockdown Cabinets; and I do hereby declare the following to be a full, clear, and exact description of the invention, such as will enable others skilled in the art to which it appertains to make and use the same.

This invention relates to knock-down cabinets and has for an object to provide a cabinet made up of sections with improved means for securing the sections separably together to form a cabinet having a great degree of rigidity when organized to form such cabinet.

A further object of the invention is to provide a cabinet which when made up in part of screened sections employs also a sufficient number of solid sections of the proper size to serve for crating and protecting the screen sections when the device is in knock-down condition.

With these and other objects in view the invention comprises certain novel constructions, combinations and arrangements of parts as will be hereinafter more fully described and claimed.

In the drawings:—Figure 1 is a perspective view of the improved cabinet organized, with parts broken away to show the manner of securing the elements together. Fig. 2 is a longitudinal vertical sectional view through the improved cabinet. Fig. 3 is a view of the improved cabinet in knock-down condition with the parts associated and crated. Fig. 4 is a perspective view of the top removed.

Like characters of reference indicate corresponding parts throughout the several views.

The improved cabinet which forms the subject matter of this application includes a front section, indicated as a whole at A, and side sections B and C. Preferably, though not necessarily, these side and front sections A, B and C are made up of frames 10 covered with fabric or screen as indicated, it being understood, however, that the construction of these sections as screened is immaterial to the present invention, the invention comprehending as well sections

composed of material which is not screened. The front section A and the side section B are connected by hinges 11, the leaf attached to the section A being long enough to permit the frame 10 of the section B to be positioned between the other leaf and the edge of the frame of the section A, as indicated more particularly in Fig. 1.

A top section D and a bottom section E are provided, having adjacent their ends on their inner faces dove-tailed grooves 12, while the upper and lower ends of the sections B and C are provided with dove-tailed tongues 13 proportioned to fit within the dove-tailed grooves 12. As shown more particularly in Fig. 4, the dove-tailed grooves are formed tapered or wedge-shaped with the dove-tailed tongues 13 formed to correspond, the wider ends of the grooves and tongues being at the front of the cabinet.

The sections A, B and C are set up as indicated in Fig. 1 and the top D placed upon the sections B and C by inserting the ends of the tongues 13 in the ends of the grooves 12 and sliding the top section toward the front. The bottom section E is put on in the same manner, preferably by inverting the structure and sliding the bottom onto the lower ends of the sections B and C in like manner.

The inner faces of the frames 10 of the sections B and C are provided near their rear edges with vertical grooves 14 and the back section F is provided along all of its edges with tongues 15. The tongues 15 along the vertical edges are inserted in the vertical grooves 14 of the sections B and C by moving the bottom section E slightly to the front and sliding the back section F upward within such grooves. The top section D is also provided with a groove 16 which receives the upper tongue of the back section F. The bottom section E is not provided with a groove similar to the groove 16 but simply made slightly thinner at its rear so that the rearward edge slides under the shoulder forming the tongue 15 at the lower edge of the back section F.

Both the top section D and the bottom section E are provided with forwardly extending flanges 17 which serve as lintel and sill respectively for the top and bottom of the door section A, such flanges being preferably produced by forming a rabbet in the front edges of the top and bottom sections.

To knock down the cabinet from its as-

sembled position as shown in Fig. 1 the door section A is first opened and the bottom section E slid forward slightly to free the back section F which is then slidably drawn down 5 out of the grooves 14 of the side sections B and C. The bottom section is then moved in the opposite direction or toward the back to release it from the tongue and groove connection with the side sections B and C, 10 and the cabinet inverted and the top removed in like manner. The side sections B and C are also preferably provided with bars 18 serving as spacers for the frames of the side sections B and C and also serving 15 to receive the ends of shelves 19 which are inserted after the cabinet is set up and are first removed when the cabinet is to be knocked down. When in knock-down position the back section F is first laid upon a 20 support with the connected sections A and B on such back, the section B being folded over upon the section A and the section C laid on the section A alongside the section B. The shelves 19 are next placed upon the 25 sections B and C and the top and bottom sections D and E placed last, which forms a crate to protect the screens of the sections

A, B and C. It will thus be apparent that in the knock-down position as shown in Fig. 3 the screened portion is protected by the 30 solid portions and the whole device is in position for convenient transportation and storage.

I claim:—

A knock down cabinet comprising duplicate sides having upright grooves in their inner faces near their rear edges and dovetailed tongues along their upper and lower ends tapering toward said edges, a top and a bottom each having tapering dovetailed 40 grooves to receive said tongues, the top having a groove in its inner face near its rear edge and the bottom being made thinner along its rear edge, a back removably engaging the grooves on the inner faces of the 45 sides and top and resting on the thin portion of the bottom, and a front movably held in place.

In testimony whereof I affix my signature in presence of two witnesses.

NIELS ANTON HANSEN.
